DESIGN FOR A MOLDING PRESS

Francis S. Farley, Westfield, N. J., assignor to
The Watson-Stillman Co., Roselle, N. J., a cor-
poration of New Jersey

Application January 5, 1940, Serial No. 89,312

Term of patent 14 years

To all whom it may concern:

Be it known that I, Francis S. Farley, a citizen of the United States of America and resident of Westfield, in the county of Union and State of New Jersey, have invented a new, original, and ornamental Design for a Molding Press, of which the following is a specification, reference being had to the accompanying drawings, forming a part thereof.

In the drawings,

Fig. 1 is a perspective view of a molding press, showing my new design;

Fig. 2 is a front elevational view of the press; and

Fig. 3 is a side elevational view of the press.

I claim:

The ornamental design for a molding press, as shown.

FRANCIS S. FARLEY.
